William A. Dobson, West Hartford, Conn., assignor to Underwood Corporation, New York, N. Y., a corporation of Delaware

Application November 24, 1948, Serial No. 149,813

Term of patent 7 years

(Cl. D64—11)

To all whom it may concern:

Be it known that I, William A. Dobson, a citizen of the United States, residing in West Hartford, in the county of Hartford and State of Connecticut, have invented a new, original, and ornamental Design for a Typewriting Machine, of which the following is a description, reference being had to the accompanying drawings, forming part thereof.

Figure 1 is a front perspective view of a typewriting machine, showing my design from the left-hand side thereof.

Figure 2 is a rear perspective view of the typewriting machine shown in Figure 1, the view being from the right-hand side thereof.

I claim:

The ornamental design for a typewriting machine, as shown.

WILLIAM A. DOBSON.
